VIBRATING SCREEN

Edwin B. Gary, Kenmore, N. Y.

Application December 20, 1939, Serial No. 310,091

9 Claims. (Cl. 209—326)

This application is a continuation in part of my co-pending application Serial No. 295,391, filed September 18, 1939.

The invention relates to a vibrating screen for separating and grading materials such as, for example, sand, gravel, crushed stone, coke and ore and more particularly the invention is concerned with improvements in screens of the type characterized by the combination of a stationary frame, a live frame and a single actuating shaft which is mounted upon the stationary frame and which carries the live frame, the actuating shaft being located substantially midway between the ends of the live frame at, or 15 in the vicinity of, the center of gravity and being operative to gyrate the live frame in a vertical path.

In order to maintain the live frame at the proper screening angle while permitting its positive gyration in the manner described it has heretofore been proposed to employ so-called equalizing springs, the latter being carried by the stationary frame and acting against the live frame at opposite sides of the actuating shaft. 20 Such a construction has the objection, however, that the springs, being more or less impositive in their action, provide what is in effect floating supports and although, to a certain degree, they resist angular movement of the live frame upon the actuating shaft they do not positively prevent it, it being obvious that if the live frame is permitted to rock as it is gyrated the paths traversed by the different sections thereof will vary as to size and shape and that the action of such sections upon the material being screened will, therefore, be non-uniform. Further objections to such a construction are that the springs are subject to frequent breakage and otherwise lose their effectiveness with continued use.

The principal object of the present invention is to overcome the above objections, this object contemplating the employment of a stabilizing mechanism which is operative to positively control the movement of the live frame in such a manner that every part is caused to traverse a path of the same circular outline and dimensions, thereby to insure a substantially uniform screening action throughout the length of the live frame.

A further object is to provide a screen which is dynamically balanced under all working conditions, and hence which may be operated at such speeds as may be necessary to effect thorough separation of the materials, damp, wet or other-

wise, without blinding and without the transmission of objectionable unbalanced impulses or vibrations to the supporting structure, this object contemplating a screen wherein the stabilizing mechanism is wholly self-sustaining 5 and does not increase the weight, or modify the distribution of the weight, of the live frame.

A still further object is to provide a novel design and arrangement of the parts of the screen, whereby compactness is achieved, simplicity and economy in construction are obtained and wearing of the parts under running conditions is minimized.

The invention is illustrated in the accompanying drawings in which:

Figure 1 is a top plan view of a vibrating screen embodying the features of the invention.

Figure 2 is a longitudinal section taken along line 2—2 of Figure 1 and shows the screen inclined at a normal working angle.

Figure 3 is an enlarged transverse section taken along line 3—3 of Figure 2.

Figure 4 is a similar section taken along line 4—4 of the same figure.

Figure 5 is an enlarged detail section taken along line 5—5 of Figure 2.

Figure 6 is an enlarged detail section of a modified form of connection for the stabilizing arms.

The stationary, or base, frame and the live frame of the screen are indicated at 10 and 11, respectively. The former comprises a longitudinal pair of spaced channel members 12 and transverse connecting members 13 and may be mounted upon or suspended from any suitable supporting structure at the desired angle of inclination. The live frame 11 includes side plates 14 between which an upper screening cloth 15 of relatively coarse mesh and a lower screening cloth 16 of relatively fine mesh are stretched, 35 the said frame being of the so-called double-deck type and being adapted, therefore, to separate the material into three grades.

The actuating shaft, indicated at 17, is adapted to support substantially the entire weight of the live frame. It is journaled in bearings 18 which are mounted upon the base frame members 12; it carries a pulley 17a by which it may be driven; and it extends through a tubular housing 19 (Figure 3) which carries the live 40 frame. The said housing is mounted between the side plates 14 midway between the ends of the live frame and between the upper and lower screening decks. Its opposite ends accommodate bearings 20 in which are journaled eccentrics 55

20a, the latter being formed or provided upon the actuating shaft adjacent its ends. When driven, therefore, the actuating shaft is operative to gyrate the live frame through a vertical path, the diameter of which is determined by the throw of the eccentrics. To the end that the inertia of the live frame will not set up moments of force about the eccentrics, the actuating shaft is preferably so located that the centers of the eccentrics lie along a line which passes through the live frame substantially at the center of gravity. Flywheels 21, which are mounted upon the actuating shaft between the sides of the live frame and the bearings 18, carry radially adjustable weights 22 for counterbalancing the eccentric load represented by the live frame, it being understood that a part of such load may be counterbalanced, if desired, by offsetting the central portion of the shaft in a direction opposite to that in which the eccentrics 20a are offset. The transmission of unbalanced impulses or vibrations to the bearings 18, and hence to the base frame and supporting structure, is thus prevented.

25 In order to maintain the live frame at the proper working angle and insure a uniform circular movement throughout its length, a stabilizing mechanism embodying the features of the invention is employed. The said mechanism, as illustrated, includes elongated arms 23 which are arranged end-to-end in pairs, one of which is located at each side of the live frame between the latter and a longitudinal member of the base frame. Each arm is provided intermediate its ends with a trunnion 24 (Figure 4). The latter is formed with an annular enlargement 25, carries a bushing 26 of relatively soft rubber or like material and is mounted in a bearing 27 which is carried by the base frame, the bearing having an annular recess in which the enlargement 25 is confined by a cap-piece 27a to prevent axial displacement of the trunnion. The inner ends of the arms, one of which overlies the other, carry studs 28 (Figure 3). The said studs are located on the sides of the arms facing the adjacent longitudinal member of the base frame; they are similar in shape to the trunnions 24; they carry bushings 29 similar to those carried by the trunnions; and they are connected by a link 30. The latter comprises companion sections which embrace the opposite side of the bushings 29 with a conforming fit and which are secured together by nut-and-bolt fastening means 31, it being noted that the studs, and hence the link, occupy a plane which extends substantially at right angles with respect to the length of the arm assembly. The outer ends of the arms are formed on the sides adjacent the live frame with studs 32 (Figure 5). The latter are connected by rods 33 to trunnions 34 which are carried by the adjacent side plate 14 of the live frame at opposite sides of, and in equidistant relation with respect to, the actuating shaft, the said rods extending substantially at right angles to the arms while the trunnions are preferably located along a center line which intersects a line passing through the centers of the eccentrics 20a. The studs 32 and the trunnions 34 are similar in shape to the trunnions 24 and they carry bushings 35 similar to the bushings 26, the connecting rods 33 fitting the bushings 35 conformably and being removably secured thereon by upper and lower cap-pieces 36 and 37, respectively. Preferably the arms 23 are balanced upon the trunnions 24, the weight of the rods and links being taken into consideration and compensated.

In other words, each arm, link and rod assembly is self-sustaining and is carried wholly by the base frame. Hence the said assemblies do not add to the weight of the live frame and do not have to be taken into consideration in the balancing of the live frame. 5

From the foregoing it will be apparent that the vertical component of the path through which the live frame is caused to travel is provided by rocking of the stabilizing arms upon the trunnions 24. Owing to their connection in the manner described, however, the arms of each pair can only move simultaneously and through the same angular distance. Their outer ends which are connected by the rods 33 to the live frame at opposite sides of the actuating shaft, therefore, can only have vertical movements which with respect to period, direction and amplitude are the same, it being noted in this connection that the links 30 rock to compensate for the slight divergence of the arcuate paths described by the inner ends of the arms. The live frame is thus restrained so that no part can move vertically at a different time, at a greater speed or through a greater range than the remaining parts. As the arms 23 are actuated in the manner described the rods 33 rock upon them to provide the horizontal component of the path traversed by the live frame. Every point in the latter, therefore, moves in a circular path of the same diameter. A uniform screening action throughout the length of the live frame and a constant working angle are thereby insured. 25

It will be noted that the angular distances through which the arms, rods and links of the stabilizing mechanism rock are relatively small as the vertical and horizontal components of the path through which the live frame is gyrated will seldom be greater than three-eighths of an inch. If preferred, therefore, the connection of the inner ends of each pair of stabilizing arms may be effected simply by a pin 38, as illustrated in Figure 6. A rubber bushing 39 which is carried by the pin will yield to compensate for the divergence of the paths traversed by the inner ends of the arms as the latter rock in the manner described, 45 it being appreciated in this connection that such divergence will, owing to the length of the arms and the shortness of the arcs, be slight, for example of the order of one-thousandth of an inch, more or less. 50

Under ideal operating conditions the live frame is substantially balanced upon the eccentrics 20a of the actuating shaft and there is a minimum load upon the arms 23 as they move with the live frame. If, however, owing to non-uniform distribution of the material being screened, or for any other reason, the resultant forces unbalance the live frame so that one end tends to move faster or through a greater distance than the other, such forces are transmitted to the stabilizing arms and tend to rock the latter so that the connected ends of each pair are biased to the same degree but in opposite directions. The unbalancing force acting upon the live frame is thus dissipated without causing angular movement of the latter upon the actuating shaft. In other words any unbalancing forces applied to the live frame merely increase the load upon the arms, rods and links of the stabilizing mechanism. They do not influence in any way the path of movement of the live frame. 70 For example, any force tending to rock the live frame in a clockwise direction upon the actuating shaft tends to rock the arms at the right end of the screen so that their inner ends are biased toward the actuating shaft and to rock the arms 75

at the left end of the screen so that their inner ends are biased away from the actuating shaft. The opposing forces, being equal and in opposite directions, neutralize one another. On the other hand, any unbalancing force tending to rotate the live frame in a counter-clockwise direction is resisted in a like manner as the inner ends of the arms at the left end of the screen are biased toward the actuating shaft and the inner ends of the arms at the right end of the screen are biased away from it.

In assembling the screen the bushings carried by the trunnions 24, those carried by the studs 23 and 32 and those carried by the trunnions 34 are all placed under a compression high enough to insure a firm, non-slipping grip between the contacting surfaces of the bushings and the connected parts. The bushings, therefore, in response to the torsional stresses to which they are subjected during operation of the screen, twist about axes parallel to the axis of the actuating shaft to permit the necessary relative angular movements between the parts of the stabilizing mechanism. Positive control of the path of movement of the live frame, without relative movement between the contacting surfaces of any of the parts of the stabilizing mechanism, is thereby achieved. Wearing of the said parts is thus prevented, lubrication is rendered unnecessary and smooth running and quiet operation of the screen are insured. In this connection it will be appreciated that use of the bushings 26, 29 and 35 as torsion elements will not increase to any appreciable degree the power required to operate the screen as the energy which is stored in the bushings during movements of the connected parts in one direction will be released when the direction of movement of the parts is reversed.

It will be apparent that the stabilizing arm-and-rod assembly at each side of the live frame, being located in a vertical plane and being carried by the base frame, is not only balanced but is wholly self-sustaining. The said assemblies, therefore, do not add to the weight, or modify the distribution of the weight, of the live frame. Hence, as the eccentric mounting of the latter is counterbalanced by the weights carried by the flywheels, the only load upon the actuating shaft is static and is the weight represented by the live frame. The latter, therefore, may be accurately balanced so that it may be operated at high speeds (including speeds at which the downward movements of the live frame are considerably faster than the acceleration of gravity of the material being screened) without the transmission of destructive, or otherwise objectionable, impulses or vibrations to the base frame or supporting structure. When the screen is properly balanced the only load to which the stabilizing mechanism is subjected is that represented by the non-uniform distribution of the material screened. The said mechanism may, therefore, be light and compact in design, it being noted in this connection that the studs at the ends of each of the arms 23 are located on opposite sides of the arm. Hence any force applied to one end of an arm which tends to tip its trunnion in one direction is neutralized by the equal, and similar, force which is applied to the opposite end of the arm. The trunnion, therefore, has no tendency to cant in its bearing.

Apart from the lightness of the stabilizing mechanism it is to be noted that as each pair of arms and the associated connecting rods oper-

ate in a vertical plane and that as all of the axes of the various pivotal connections are parallel to the axis of the actuating shaft, the longitudinal members of the base frame may be arranged as close to the sides of the live frame as the flywheels will permit. This renders the construction compact and has the further advantage that whipping of the shaft is minimized.

I claim as my invention:

1. A vibrating screen comprising a supporting frame, a live frame, said live frame having sides between which a screening element is stretched, a horizontal actuating shaft carried by the supporting frame, said shaft passing through said sides, having eccentrics upon which the live frame is mounted and being so located that the centers of the eccentrics lie along a line substantially coincident with the center of gravity of the live frame, means for driving said shaft to thereby gyrate said live frame in a vertical path, means carried by said shaft for counterbalancing the eccentric mounting of said live frame, stabilizing arms arranged lengthwise of said live frame in end-to-end relation and individually mounted on said supporting frame for rocking movement in vertical planes, rods arranged substantially at right angles with respect to said arms, said rods having pivotal connections with the outer ends of said arms and with said live frame at opposite sides of said shaft and means connecting the inner ends of said arms so that their angular movements, although in opposite directions, are simultaneous and of substantially the same amplitude, thereby maintaining said live frame in the proper screening position and effecting a substantially uniform gyratory movement throughout its length despite non-uniform distribution of the load and other forces which tend to cause it to rock in a vertical plane.

2. A vibrating screen comprising a supporting frame, a live frame, a horizontal actuating shaft carried by the supporting frame, said shaft being located substantially midway between the ends of said live frame and having eccentrics upon which the latter is mounted, means for driving said shaft to thereby gyrate said live frame in a vertical path, stabilizing arms arranged lengthwise of said live frame in end-to-end relation and individually mounted for rocking movement in vertical planes, links arranged substantially at right angles with respect to said arms, said arms and links being pivotally connected to one another and the assembly thus provided having pivotal connections with the supporting frame and with said live frame at opposite sides of said shaft and means connecting the adjacent ends of said arms so that their angular movements, although in opposite directions, are simultaneous and of substantially the same amplitude, thereby maintaining said live frame in the proper screening position and effecting a substantially uniform gyratory movement throughout its length despite non-uniform distribution of the load and other forces which tend to cause it to rock in a vertical plane.

3. A vibrating screen comprising a supporting frame, a live frame, a horizontal actuating shaft carried by the supporting frame, said shaft being located substantially midway between the ends of said live frame and having eccentrics upon which the latter is mounted, means for driving said shaft to thereby gyrate said live frame in a vertical path, stabilizing arms arranged lengthwise of said live frame in end-to-end relation and individually mounted on said supporting frame.

frame for rocking movement in vertical planes, rods arranged substantially at right angles with respect to said arms, said rods having pivotal connections with the outer ends of said arms and 5 with said live frame at opposite sides of said shaft and means connecting the inner ends of said arms so that their angular movements, although in opposite directions, are simultaneous and of substantially the same amplitude, thereby 10 maintaining said live frame in the proper screening position and effecting a substantially uniform gyratory movement throughout its length despite non-uniform distribution of the load and other forces which tend to cause it to rock in a 15 vertical plane.

4. A vibrating screen comprising a supporting frame, a live frame, a horizontal actuating shaft carried by the supporting frame, said shaft having eccentrics upon which the live frame is 20 mounted and being so located that the centers of the eccentrics lie along a line substantially coincident with the center of gravity of the live frame, means for driving said shaft to thereby gyrate said live frame in a vertical path, stabilizing arms arranged lengthwise of said live frame in end-to-end relation, having overlapping inner ends, and being individually mounted on said supporting frame for rocking movement in vertical planes, rods arranged substantially at 25 right angles with respect to said arms, said rods having pivotal connections with the outer ends of said arms and with said live frame at opposite sides of said shaft and means connecting the inner ends of said arms so that their angular 30 movements, although in opposite directions, are simultaneous and of substantially the same amplitude, thereby maintaining said live frame in the proper screening position and effecting a substantially uniform gyratory movement throughout its length despite non-uniform distribution of the load and other forces which tend to cause it to rock in a vertical plane.

5. A vibrating screen comprising a supporting frame, a live frame, a horizontal actuating shaft 45 carried by the supporting frame, said shaft being located substantially midway between the ends of said live frame and having eccentrics upon which the latter is mounted, means for driving said shaft to thereby gyrate said live frame in a vertical path, elongated stabilizing arms arranged 50 lengthwise of said live frame in end-to-end relation and individually mounted substantially midway between their ends upon said supporting frame for rocking movement in vertical planes, rods arranged substantially at right angles with 55 respect to said arms, said rods having pivotal connections with the outer ends of said arms and with said live frame at opposite sides of said shaft and means connecting the inner ends of said arms so that their angular movements, although 60 in opposite directions, are simultaneous and of substantially the same amplitude, thereby maintaining said live frame in the proper screening position and effecting a substantially uniform gyratory movement throughout its length despite non-uniform distribution of the load and other forces which tend to cause it to rock in a vertical plane.

6. A vibrating screen comprising a supporting 70 frame, a live frame, a horizontal actuating shaft carried by the supporting frame, said shaft being located substantially midway between the ends of said live frame and having eccentrics upon which the latter is mounted, means for driving said shaft to thereby gyrate said live

frame in a vertical path, a pair of stabilizing arms arranged in end-to-end relation at each side of and lengthwise of said live frame, each of said arms being individually mounted intermediate its end upon said supporting frame for 5 rocking movement in a vertical plane, rods arranged substantially at right angles with respect to said arms, said rods having pivotal connections with the outer ends of said arms and with both sides of said live frame at opposite sides of said 10 shaft and means connecting the inner ends of said pairs of arms so that the angular movements of the arms of each pair, although in opposite directions, are simultaneous and of substantially the same amplitude, thereby maintaining said 15 live frame in the proper screening position and effecting a substantially uniform gyratory movement throughout its length despite non-uniform distribution of the load and other forces which tend to cause it to rock in a vertical plane. 20

7. A vibrating screen comprising a supporting frame, a live frame, a horizontal actuating shaft carried by the supporting frame, said shaft being located substantially midway between the ends of said live frame and having eccentrics 25 upon which the latter is mounted, means for driving said shaft to thereby gyrate said live frame in a vertical path, stabilizing arms arranged lengthwise of said live frame in end-to-end relation and pivotally mounted upon said 30 supporting frame for rocking movement in vertical planes, rods arranged substantially at right angles with respect to said arms, said rods having pivotal connections with the outer ends of said arms and with said live frame at opposite 35 sides of said shaft and means including a pivot pin for connecting the inner ends of said arms so that their angular movements, although in opposite directions, are simultaneous and of substantially the same amplitude, thereby maintaining 40 said live frame in the proper screening position and effecting a substantially uniform gyratory movement throughout its length despite non-uniform distribution of the load and other forces which tend to cause it to rock in a vertical plane, 45 the axis of said pivot pin being parallel to the axis of said shaft.

8. A vibrating screen comprising a supporting frame, a live frame, a horizontal actuating shaft carried by the supporting frame, said shaft being located substantially midway between the 50 ends of said live frame and having eccentrics upon which the latter is mounted, means for driving said shaft to thereby gyrate said live frame in a vertical path, stabilizing arms arranged lengthwise of said live frame in end-to-end relation, being pivotally mounted upon said supporting frame for rocking movement in vertical planes and having overlapping inner ends, rods arranged substantially at right angles with respect to said 55 arms, said rods having pivotal connections with the outer ends of said arms and with said live frame at opposite sides of said shaft and a link connecting the inner ends of said arms, said link having spaced pivot pins located in a plane which 60 extends substantially at right angles with respect to the length of the arm assembly and having axes parallel with the axis of said shaft so that the angular movements of said arms, although 65 in opposite directions, are simultaneous and of substantially the same amplitude, thereby maintaining said live frame in the proper screening position and effecting a substantially uniform gyratory movement throughout its length despite non-uniform distribution of the load and other forces 70

which tend to cause it to rock in a vertical plane.

9. A vibrating screen comprising a supporting frame, a live frame, a horizontal actuating shaft carried by the supporting frame, said shaft being located substantially midway between the ends of said live frame and having eccentrics upon which the latter is mounted, means for driving said shaft to thereby gyrate said live frame in a vertical path, stabilizing arms arranged lengthwise of said live frame in end-to-end relation and individually mounted for rocking movements in vertical planes, links arranged substantially at right angles with respect to said arms, said arms and links being pivotally connected to one another and the assembly thus provided having pivotal connections with said supporting frame and with said live frame at opposite sides of said

shaft, torsion elements of rubber or the like which are held under compression between the parts of said connections and which are adapted to twist about axes parallel with the axis of said shaft to permit relative angular movement between said parts and means connecting the inner ends of said arms so that their angular movements, although in opposite directions, are simultaneous and of substantially the same amplitude, thereby maintaining the live frame in the proper screening position and effecting a substantially uniform gyroscopic movement throughout its length despite non-uniform distribution of the load and other forces which tend to cause it to rock in a vertical plane.
